DISPLAY DEVICE

John S. Connors, Cleveland, Ohio

Application May 12, 1938, Serial No. 207,539

4 Claims. (Cl. 211—138)

This invention relates to a display device or stand which is particularly adapted for use in displaying articles of manufacture or advertising matter in an effective manner. One of the objects 5 of the invention is to provide a display device of the character described which is simple in construction, rigid and dependable in operation and well adapted for production at comparatively low cost.

10 Another object of the invention is to provide a display device of the character described which is readily adjustable to different positions so that articles or advertising matter may be displayed at the desired angle.

15 A further object of the invention is to provide a display device of the character described which consists of a main section adapted to support articles to be displayed and a prop section pivotally and slidably connected with the main section 20 and adapted to position and support the main section in different angular positions with only a minimum amount of adjustment.

A further object of the invention is to provide a display device of the character described which 25 consists of a main section adapted to maintain or support articles or advertising matter to be displayed and a prop section which is pivotally and adjustably secured to the main section and adjustable with respect thereto and which has a 30 cam surface adapted to cooperate with an adjacent surface on the main section to provide automatic locking means for holding the device in the desired angular position.

A still further object of the invention is to provide 35 a display rack or stand which has shelves thereon adapted to support articles to be displayed and a prop section adjustable to support the stand in different angular positions, there being a mechanical connection between the prop 40 and the shelves for adjusting the position of the shelves when the prop is moved from one position to another to maintain the shelves level.

Further and more limited objects of the invention will appear as the description proceeds and 45 by reference to the accompanying drawings in which Fig. 1 is a view in front elevation of the preferred embodiment of my display stand with an article support thereon; Fig. 2 is a view in side elevation of the stand shown in Fig. 1; Fig. 3 50 is a sectional view on the line 3—3 of Fig. 2; Fig. 4 is a fragmentary sectional view illustrating different positions of the prop member which supports the stand; Fig. 5 is a perspective view of a modified form of my invention looking at the 55 rear thereof which is preferably formed of card-

board or the like; Fig. 6 is a detail view showing the section which receives the prop; Fig. 7 is a view in side elevation of a further modified form of a display stand embodying shelves and supporting articles to be displayed; Fig. 8 is a view in rear elevation of the display stand shown in Fig. 7; and Fig. 9 is a view similar to Fig. 1 with the stand supported in a different angular position.

Referring now to the drawings, Figs. 1-4 inclusive, the preferred embodiment of my invention consists of a display stand made up of a main section and a prop section pivotally and slidably secured to the main section and adapted to be positioned to support the main section in 10 different angular positions. The main section preferably consists of a wire frame having an upper rectangular portion 1 and a lower rectangular portion 2 the lower edge of which is turned upwardly as shown at 3. The central portion of the 15 wire frame is contracted and fitting thereover is a formed metal sleeve 4 which holds the wire frame together and which has a rear edge thereof tapered as shown at 5. Slidably mounted on the sleeve 4 is a collar 6 which has a pair of arms 7 and 8 between which is pivotally mounted a prop 9 by means of a bolt or pin 10. The upper end of the prop 9 is shaped to provide a cam surface 11 which engages the tapered surface 5 to provide automatic locking means for holding the 20 prop in the desired adjusted position. The sleeve 4 may have suitable indicia thereon to indicate the angular position which the main section will assume when the prop is in any one of several 25 desired positions. The angular position of the 30 main section may be adjusted by merely sliding the collar 6 upon the sleeve 4. The collar is freely slidable upon the sleeve when the prop is moved to disengage the cam surface thereof from the tapered surface 5. It will therefore be seen 35 that a large angular adjustment of the main section may be attained by a very slight movement of the collar 6 on the sleeve 4. The main section is adapted to support articles or advertising matter to be displayed.

45 It will now be clear that I have provided a display stand which is very simple in construction and capable of being adjusted to various angular positions with a minimum of effort and that the stand when adjusted is automatically locked in 50 the adjusted position.

In Figs. 5 and 6 there is disclosed a modified form of my invention which is preferably formed of cardboard or the like. This form of the invention consists of a main section 12 and an 55

auxiliary section 13 the rear face of which is tapered as shown at 14 and has therein an angular slot 15. The sections 12 and 13 are preferably formed of one piece of cardboard and are hinged together so that they may be moved to the position shown in Fig. 5. The section 12 may constitute an easel adapted to support a display board 16 which, if desired, may be permanently secured to the section 12. In order to hold the section 13 in the desired position with respect to the section 12, suitable cut-out sections 17 and 18 are provided which may be folded to the position shown in Fig. 5 to hold the section 13 in the desired position. Slidably and adjustably mounted in the slot 15 is a member 19 to which the prop 20 is pivotally secured by means of a suitable pin or bolt 21. The upper end of the prop has a cam surface indicated by the reference character 22 which engages the tapered surface 14 of the section 13 when the stand is disposed in the position shown in Fig. 5. It will be seen that the prop is adjustable longitudinally of the slot and that the cam surface 22 engages the tapered surface 14 to automatically lock the prop in the desired position whereby to maintain the stand in the desired angular position. It will be seen that a small longitudinal movement of the member 19 in the slot 15 will provide for a wide variation in angular positions of the stand. This form of the invention in function and operation is substantially the same as the form of the invention disclosed in Figs. 1-4 inclusive, but is better adapted to be formed of cardboard or some similar light material.

In Figs. 7-9 inclusive I have disclosed a second modification of my invention in which the stand is provided with adjustably mounted shelves for displaying articles of merchandise. In this form of my invention the main section of the stand consists of a plate 25 which is preferably formed of metal and which has therein a plurality of pairs of elongated slots 26 and 27 which receive therein the supporting shelves. The shelves 29 are preferably formed of a length of wire bent to shape as shown most clearly in Fig. 8 and each shelf has a pair of rearwardly projecting portions 29^a which have teeth 30 which engage the lower edges of the slots to hold the shelves in the desired adjusted position. The plate 25 is also provided at each side thereof with a pair of rearwardly bent portions 31 and 32 which have apertures therein which slidably receive a pair of bars 33 and 34. The bars 33 and 34 have a plurality of elongated openings 35 therein which receive the rearwardly projecting portions 29^a of the shelves. The back of the plate 25 has a cut-out portion 36 which is bent rearwardly and which has an angular slot 37 therein. The rear face of the plate 36 is tapered as shown at 38. Slidably freely in the slot 37 is a member 39 to which is pivotally secured a prop 40 by means of a pin 41. The upper end of the prop has a cam surface 42 which engages and cooperates with the tapered surface 38 to lock the stand in the desired angular position. The prop 40 has a curved extension 43 thereon in which is provided a curved slot 44. Extending transversely of the stand is a rod 45 the opposite ends of which extend through circular openings provided in the bars 33 and 34. When the stand is moved from the position shown in Fig. 7

to the position shown in Fig. 9, the rod 45 being engaged with the bars 33 and 34 through which the projecting ends 29^a of the shelves extend, causes the shelves to be maintained in the horizontal position. In other words, connections are provided between the prop and the shelves for adjusting the positions of the shelves when the prop is moved from one position to another so as to maintain the shelves in the horizontal position. The position of the shelves with respect to the plate 25 may be adjusted and the teeth 30 on the projecting ends 29^a of the shelves hold the same in the adjusted positions.

It will now be clear that I have provided a display stand or rack which will accomplish the objects of the invention hereinbefore stated. It is to be understood that the embodiments of the invention herein disclosed are to be considered merely as illustrative and not in a limiting sense as various changes may be made in the details of construction and arrangement of parts without departing from the spirit of my invention. The invention therefore is limited only in accordance with the scope of the appended claims.

Having thus described my invention, what I claim is:

1. A display device comprising a main section and a prop pivotally and slidably secured to said main section and adapted to be positioned to support said main section in different angular positions, the upper end of said prop having a cam surface and the adjacent portion of said main section having a tapered surface adapted to be engaged by said cam surface to provide automatic locking means for holding said prop in the desired position.

2. A display device comprising a frame, a member secured to said frame and having a tapered surface at the back thereof, a second member slidably loosely on said frame, a prop pivotally secured to said second member and having a cam surface at the upper end thereof adapted to engage said tapered surface to form locking means for automatically securing said prop in the desired position whereby to support said frame in the desired angular position.

3. A display device comprising a front portion containing a display, a member secured to the back of said front portion and having an elongated slot therein and a tapered rear face, a second member freely slidably in said elongated slot, a prop pivotally secured to said second member and having a cam surface at the upper end thereof adapted to engage the tapered rear face of said first member and providing automatic locking means for holding said prop in the desired position.

4. A display device comprising a wire frame shaped to provide a support for an article to be displayed, a metal member surrounding a portion of said frame and having a rear face which is tapered, a collar slidably freely on said member, a prop pivotally secured to said collar and having a cam surface at the upper end thereof which engages said tapered face to provide automatic locking means for said prop whereby said frame may be supported in different angular positions.

JOHN S. CONNORS. 70
